US00D549722S

(12) **United States Design Patent** (10) Patent No.: **US D549,722 S**
Ito et al. (45) Date of Patent: **** Aug. 28, 2007**

(54) **GRAPHIC USER INTERFACE FOR DISPLAY FOR CONSTRUCTION MACHINE**

(75) Inventors: **Eitaro Ito**, Kokubunji (JP); **Tsutomu Fujii**, Yokohama (JP); **Kenichi Sagiya**, Chikusei (JP); **Yasushi Tokuda**, Kasumigaura (JP); **Yutaka Watanabe**, Kasumigaura (JP); **Takao Kurosawa**, Ushiku (JP)

(73) Assignee: **Hitachi Construction Machinery Co., Ltd.**, Tokyo (JP)

(**) Term: **14 Years**

(21) Appl. No.: **29/268,957**

(22) Filed: **Nov. 17, 2006**

(51) LOC (8) Cl. **14-04**

(52) U.S. Cl. **D14/488**

(57) **CLAIM**

We claim the ornamental design for graphic user interface for display for construction machine, as shown.

DESCRIPTION

The FIGURE is a front elevational view of a graphic user interface for display for construction machine, showing our new design.

The broken line portions of the drawing are for illustrative purposes only and form no part of the claimed design.
